CLAIM

The ornamental design for a cannula for removal of fat tissue, as shown and described.

DESCRIPTION

FIG. 1 is a perspective side view of a cannula for removal of fat tissue showing my new design;

FIG. 2 is a distal end view of the cannula for removal of fat tissue thereof;

FIG. 3 is a proximal end view of the cannula for removal of fat tissue thereof;

FIG. 4 is top view of the cannula for removal of fat tissue thereof;

FIG. 5 is a bottom view of the cannula for removal of fat tissue thereof;

FIG. 6 is a left side view of the cannula for removal of fat tissue thereof; and,

FIG. 7 is a right side view of the cannula for removal of fat tissue thereof.

1 Claim, 2 Drawing Sheets
